OUTLET VALVE FOR WATER CLOSET TANKS

Filed May 2, 1919

Patented May 29, 1923.

1,457,018

UNITED STATES PATENT OFFICE.

ALEXANDER A. CARSON, OF BRAINTREE, MASSACHUSETTS.

OUTLET VALVE FOR WATER-CLOSET TANKS.

Application filed May 2, 1919. Serial No. 294,181.

To all whom it may concern:

Be it known that I, ALEXANDER A. CARSON, a citizen of the United States, residing at Braintree, in the county of Norfolk and 5 State of Massachusetts, have invented new and useful Improvements in Outlet Valves for Water-Closet Tanks, of which the following is a specification.

This invention has relation to outlet 10 valves for water-closets, and more particularly to those employed in "low down" tanks so-called, for controlling the supply of water for flushing siphon closets.

In the modern siphon closet, it is desirable that the bowl of the closet should contain a pool of water approximately level 15 with the dam located at the junction of the up and down limbs of the siphon, to constitute a trap or water seal, and various more 20 or less complicated contrivances have been employed to refill the bowl after it has been flushed, or else only that water which remains in the outlet pipe, after the valve is closed, is depended on to effect the refill. In 25 the low-down tank, however, the outlet pipe is relatively small in diameter, e. g. not over two inches, and at best contains a small head of water, so that, when the valve is closed, there is insufficient water contained 30 therein properly to refill the bowl after the siphon breaks, especially if the break occurs at or after the closing of the valve.

The object of the present invention is to ensure the delivery of a sufficient amount of 35 water to refill the bowl, subsequent to the breaking of the siphon. In the present case, this is secured by the employment of a float-controlled valve, so located and operated as to close only after the flow of 40 water from the tank has diminished to such a degree as to cause the siphonic action of the closet to cease and the refill to take place. More specifically the float is located approximately at the bottom of the tank or 45 near the level of the outlet so that it will not release the valve for closing the outlet, until the solid column of water in the outlet pipe has broken, and the supply water is insufficient to fill such pipe. In such case, 50 the water trickles down the wall of the pipe, and refills the bowl, before the valve closes.

On the accompanying drawing,—

Figure 1 represents a portion of the low- 55 down water-closet tank, and an outlet valve mechanism, all embodying my invention.

Figure 2 represents a plan view of the valve mechanism.

I have not shown the siphon water-closet or the entire outlet pipe, for they are well 60 known articles of manufacture and their installation in reference to the tank is too familiar to need illustration.

A portion of the low-down tank is shown, 65 however, and it has a bottom wall 10 with an aperture 11, and an end wall 12. The tank may have the usual sheet metal lining (not shown).

The valve mechanism (to the details of 70 which my invention is not limited) comprises a casting including an annular threaded nipple 15 which, as ordinarily, passes through the aperture 11, and is provided with a washer 16 and lock nut 17 to clamp the base 14 and an annular packing 18 against the bottom wall 10. The outlet pipe 19, as shown by the dotted lines, is secured to the nipple and leads to the flushing inlet of the siphon water-closet.

Rising from the base 14 is a tubular flange 20 which constitutes a seat for a valve shown 80 at 21 and subsequently to be described. 22 indicates the usual overflow standpipe, which at its lower end extends into an elbow 23. The bore of the elbow communicates with 85 the interior of the flange 20 (as indicated by dotted lines), below the upper end thereof, so that water overflowing from the tank (due to leakage of the inlet cock or otherwise) will be discharged into the tank outlet. 90

Two diametrically opposite uprights or standards 24 are cast integrally with the base and elbow, and upon them is secured, at a distance above the flange 20, a cross bar 25. This bar is provided with an annular elongated boss 26 which serves as a tubular guide for a valve stem 27 connected to the valve 21. The valve consists of two disks *a* and *b* of metal, and an interposed disk *c* of packing material to fit upon the 100 valve seat afforded by the upper end of the annular flange 20. The stem 27 passes through the center of the valve, and has two nuts 28, 29, which clamp the valve between them and secure it adjustably to the 105 stem. The upper end of the stem is bent or hooked as at 30 for connection with the usual operating handle (not shown) by which the valve is lifted. When the valve is manually raised, it is maintained in that 110 position by a float-controlled latch, consisting of a two-armed lever, one arm 31 of

which is bevelled to constitute a trigger for engagement with a double-bevelled shoulder 32 on the valve stem 27, and the other arm 33 is formed to receive a rod 34 having a float 35 on the end thereof. The two arms are angular as shown,—the lever as a whole being pivoted or fulcrumed upon a screw pin 36 passed through lugs or ears 37 formed on the cross bar 25. For the purpose of limiting the movement of the arm 31 to its dotted line or valve-locking position, it has a finger 38 to engage the guide 26. Assuming that the tank is full, and that the valve is closed, on lifting the stem completely to raise the valve, the bevelled end or single abutment face of the trigger or arm 31 slips under the shoulder 32 and holds the valve open, the buoyancy of the submerged float maintaining the arm in place. When the level of the water drops to a point where the float moves the arm from the dotted line position to the full line or valve-releasing position, the valve is released and drops on its seat. The outlet in the present instance comprises the tubular flange or seat, and the nipple, to which is connected the outlet or flushing pipe.

The parts are all so related and positioned that the float is close to the bottom of the tank,—standing ordinarily in the position shown in dotted lines, near the level of the valve seat of the outlet,—and maintains the valve in its opened position until the level of the water in the tank is just a little higher than the valve seat, and, in fact, is so low and reduced in head as not to fill the outlet. Hence, as the level of the water in the tank is lowered, due to the flow of water in the outlet pipe in practically a solid column in sufficient volume to start and maintain the siphonic discharge of the closet,—it reaches a plane where the inflow into the outlet is insufficient to fill the outlet and pipe. The diminishing supply of water is not sufficient to maintain the siphonic discharge from the closet and the siphon breaks. This occurs approximately when or just before the water reaches the level α — α in Figure 1. Then the water continues to flow into the outlet in greatly diminished volume, insufficient however to start or maintain siphonic action in the closet, and, as the level of the water drops to that shown, the float 35 drops with it, until the arm or trigger 31 releases the valve stem and permits the valve to close. The water thus supplied is sufficient to refill the closet bowl before the valve closes.

The construction as hereinbefore described and illustrated on the drawings is one in which the valve 21 is located in axial alinement with the outlet and it is loosely guided in the elongated boss 26 so that when the valve is permitted to drop it will accurately seat itself upon the valve seat being held

thereagainst by the pressure of water. It is important that the latch or arm 31 should not bear at any time against the stem 27 itself, when the valve is seated, so as to lift the valve on one side and thereby permit the escape of water. Where metal parts are necessarily submerged in the water there is always more or less corrosion and it is well known that there can be no tight sliding fit between the guide 26 and the stem 27. When the tank is filled with water the float 35 by reason of its buoyancy constantly exerts considerable pressure against the arm 34 and if the arm 31 is in engagement with the stem above the double beveled shoulder 32, the stem would be thrust or rocked laterally so as to lift the valve slightly from its seat at one side. Consequently the finger 38 performs an important function. It permits the end of the arm or latch 31 to engage only the shoulder 32 on the stem and prevents the arm from engaging the stem itself above the shoulder. In other words, this finger is located in such relationship to the elongated boss 26 that under normal conditions when the tank is full and the float tends to move upwardly, the finger engages the boss and holds the end of the arm 31 away from the stem 27 sufficiently to permit the valve to seat itself firmly against its seat.

What I claim is:

The combination of a tank, an outlet therefrom for supplying water for the siphonic discharge of a water-closet, a valve associated with said outlet and having a central shouldered stem by which it may be bodily raised, a stationary guide for loosely engaging and guiding said stem as the valve is moved toward and away from said outlet, a pivoted latch having only a single abutment face for engaging only said shoulder on the stem and locking said valve in fully open or raised position, said latch having a finger or stop to engage said stationary guide and prevent said latch from bearing against said stem when said valve is closed, and a float connected to said latch to cause the same to engage and release the shoulder on the stem of said valve, said float and latch being rigidly connected and so related, and said float being so located in respect of said outlet, that said latch will not release said valve from its fully open or raised position until after the level of the water in the tank has been lowered to a plane at which the flow of water through said outlet is insufficient to fill the same or to maintain said siphonic discharge, whereby a diminished volume of water is delivered through such outlet to refill the bowl before the valve is released and closed.

In testimony whereof I have affixed my signature.

ALEXANDER A. CARSON.
